UNITED STATES PATENT OFFICE.

JOHN YETTON AND WILLIAM ERNEST BROCKETT, OF STRATFORD, LONDON, ENGLAND.

HOLDER FOR WIRE-STAPLE BELT-FASTENERS.

1,257,061.

Specification of Letters Patent. Patented Feb. 19, 1918.

Application filed October 12, 1917. Serial No. 196,981.

To all whom it may concern:

Be it known that we, JOHN YETTON and WILLIAM ERNEST BROCKETT, subjects of the King of Great Britain and Ireland, residing at Marshgate Engineering Works, Marshgate Lane, Stratford, London, in the county of Essex, England, have invented new and useful Improvements in Holders for Wire-Staple Belt-Fasteners, of which 10 the following is a specification.

The invention relates to holders for belt-fasteners of the kind known as wire staple belt-fasteners.

Holders for wire staple belt-fasteners consist of suitably shaped strips of metal or other material in which the fasteners are held in assembled position and sold in such form. These strips or holders are generally provided with slots, projections or corrugations by means of which the fasteners are guided as they are clenched or secured to the ends of belts. Such slots, projections and corrugations only serve, as the fasteners are being clenched or secured to a belt, as 20 lateral supports for the rear ends and the diverging limbs of the fasteners. It is however desirable, especially in the case of belts which offer a considerable resistance, that a holder for wire staple belt-fasteners 25 should be such that the inwardly projecting parts of the fasteners, that is to say the parts projecting from the front ends of the diverging limbs of the fasteners, shall be laterally supported during the whole or 30 the greater part of the time that they are being driven or forced into the end of a belt.

According to the present invention holders or carriers for wire staple belt-fasteners 40 are constructed in such manner that not only are the rear bent parts and the diverging limbs of the fasteners laterally supported but also the inwardly bent portions thereof.

45 As a result of this construction the inwardly bent parts of the fasteners will correctly penetrate the substance of a belt, and when the clenching operation is completed all parts of the fasteners will lie in 50 planes coincident with the center lines of the fasteners.

The improved holder may, for example, consist of a strip of metal bent to such shape as to provide five sides or walls which 55 more or less conform to five of the sides of a regular hexagon. Two of the walls of

said strip serve as abutments for the diverging limbs of the fasteners, while the remaining three walls of the strip are formed with slots. One of these sets of 60 slots, namely the slots in the rear wall of the strip, that is to say the wall intervening between the walls which serve as abutments for the limbs of the fasteners, serve as lateral supports for the rear bent parts of 65 the fasteners, while the other two sets of slots serve as lateral supports for the front ends of the limbs of the fasteners and the inwardly bent parts of the fasteners. The rear wall of the strip may either be flat or 70 be bent in the direction of the front or open part of the holder.

The accompanying drawings illustrate a holder fulfilling the purposes of the present invention and made in the form just described.

Of these drawings, Figure 1 is an end view of said holder and Fig. 2 is a transverse section thereof, the section being taken through the slots formed in said holder. Figs. 3 and 80 4 are views corresponding to Figs. 1 and 2 but showing the wire staple belt-fasteners in position in the holder. Fig. 5 is a plan of the strip from which would be formed the holder shown in Figs. 1 to 4. 85

Referring now to these drawings, a holder fulfilling the purpose of the present invention preferably consists of a strip of metal which is bent to such shape as to provide five sides or walls 1, 2, 3, 4 and 5 which, as will 90 be seen from an inspection of Figs. 1 to 4, more or less conform to the sides of a regular hexagon. Two of these sides or walls 2 and 4, serve as abutments, see Fig. 4, for the diverging limbs of the fasteners, while 95 the remaining sides 1, 3 and 5 are formed with slots 6, 7 and 8. Of these slots, the slots 6 in the rear wall 3 of the holder serve as lateral supports for the rear bent parts of the fasteners, 9, while the slots 7 and 8 serve 100 as lateral supports for the front ends of the limbs of the fasteners 9 and the inwardly bent parts of said fasteners.

A holder of the shape illustrated by Figs. 1 to 4 would be formed by bending at the 105 proper parts a metal strip such as shown by Fig. 5, in which the parts at which the strip is bent are indicated by chain lines and the slots in and the parts of said strip corresponding to the slots and sides or walls of 110 the holder are indicated by the same reference numerals.

The rear wall 3 of the holder illustrated by Figs. 1 to 4, instead of being straight, as shown, may be curved or bent in the direction of the front or open part of the holder.

5 A holder of the general form shown in Figs. 1 to 4 possesses the advantage that a rod or pin is not necessary for the purpose of retaining the fasteners in the holder, as the final bending operation, viz, that by 10 which the sides or walls 1 and 5 are bent toward one another, secures the fasteners within the strip. Such a rod or pin may however be used.

15 However it is desirable during the operation of driving or forcing the fasteners into a belt end to pass a rod, of a diameter equal to the thickness of the belt, between the back of the holder and the bent parts of the fasteners in order to insure that the looped parts 20 of the fasteners, projecting beyond the edge of the belt end, shall, as they are formed, be made of the proper shape.

Having now described our invention what 25 we have invented and desire to secure by Letters Patent of the United States is as follows:—

1. In combination, a staple having reversely disposed prongs formed thereon, and

Copies of this patent may be obtained for five cents each, by addressing the "Commissioner of Patents, Washington, D. C."

a holder comprising means for contacting with and preventing lateral movement of 30 said prongs with relation to the shanks on which they are formed when forcing said staple into any material.

2. A holder for wire staple belt-fasteners consisting of a strip of metal or other suitable material bent to a shape more or less conforming to five of the sides of a regular hexagon and provided with slots in its two outermost walls and its rearmost wall, the 40 remaining two walls of the bent strip, between said outermost and rearmost walls being unslotted, substantially as described.

3. In combination, a staple formed of a single length of wire and comprising rear bent parts, divergent limbs and inwardly bent parts, and a holder having terminal slotted portions receiving and contacting with the limbs and the said inwardly bent parts for preventing lateral displacement of 45 said inwardly bent parts and limbs when 50 the staple is being driven into a belt.

In testimony whereof we have signed our names to this specification.

JOHN YETTON.

WILLIAM ERNEST BROCKETT.
